SLACK ADJUSTER

Walter R. Polanin, Chicago, Ill., assignor to American Steel Foundries, Chicago, Ill., a corporation of New Jersey

Filed Jan. 26, 1959, Ser. No. 788,851

13 Claims. (Cl. 188—203)

This invention relates to slack adjusters and more particularly to slack adjusters for railway vehicle brake arrangements.

The invention comprehends a slack adjuster of either the manual or automatic type, which is operable to support a brake lever fulcrumed thereto.

It is a primary object of the invention to provide, in a slack adjuster adapted to vary the fulcrum point of a brake lever, structure which will enable the slack adjuster to support the lever and accommodate the lineal movement of the lever thereon.

A more specific object of the invention is the provision of a slack adjuster structure including one or more fulcrum elements pivotally connected to the supported brake lever and disposed for sliding or rolling movement upon a track presented by the slack adjuster structure.

These and other objects of the invention will be apparent from an examination of the following description and drawings, wherein:

FIGURE 1 is a fragmentary side elevational view, with portions of the structure shown in vertical section, of a slack adjuster arrangement embodying features of the invention;

FIGURE 2 is a top plan view of the structure illustrated in FIGURE 1;

FIGURES 3 and 4 are end elevational views of the structure illustrated in FIGURE 1, as seen from the left and right, respectively;

FIGURE 5 is an enlarged view similar to FIGURE 1, but showing only that portion of the structure necessary to illustrate a modified form of the invention, and

FIGURE 6 is a schematic diagram illustrating one application of a slack adjuster, embodying features of the invention, to a railway vehicle brake arrangement.

It will be understood that certain elements have been intentionally omitted from certain views where they are better illustrated in other views.

Referring now to the drawings for a better understanding of the invention and particularly to FIGURE 6, it will be seen that a slack adjuster embodying features of the invention is shown in connection with a brake arrangement applied to a railway car truck having a frame, indicated generally at 10, supported on a pair of wheel and axle assemblies 12, each of which includes a pair of wheels 14, only one of which is shown. It will be understood, of course, that the diagrammatic arrangement of FIGURE 6 is shown only to illustrate one of many brake arrangements with which a slack adjuster embodying features of the invention may be employed, and that the novel adjuster is not in any way restricted to use with any one particular brake linkage arrangement.

As seen in FIGURE 6, there are disposed inwardly adjacent the respective wheels 14 a pair of brake shoe assemblies 16 and 17. Actuation of the brake shoe assemblies is achieved by a pair of live and dead brake levers 18 and 20 which are pivotally connected by pins 22 and 24 to the left and right hand brake shoe assemblies 16 and 17, respectively. The brake levers may be interconnected at their lower ends by means of a compression rod 26 pivotally connected at opposite ends by pins 28 and 30 to levers 18 and 20, respectively.

At its upper end, live brake lever 18 may be pivotally connected by a pin 32 to a rod 34 extending from a power

2

cylinder 36. The upper end of dead brake lever 20 may be fulcrumed by a pin 38 to a slack adjuster indicated generally at 40. It will be understood that although the location of pin 38 varies with the amount of slack in the linkage, this location is constant for each application of the brake so that brake lever 20 is in reality a dead brake lever having a fixed fulcrum relative to the car truck.

Turning now to FIGURES 1-4 of the drawings, it will be seen that slack adjuster 40 comprises a pair of preferably integral generally cylindrical housings 42 and 44 which are disposed at right angles to each other with the housing 44 being disposed below the housing 42. Protruding from one side of upper housing 42 is a preferably integral, generally flat, mounting flange 46 which may be provided with a plurality of bolt holes 48 to facilitate detachable mounting of the slack adjuster to the frame of a railway vehicle in any desired location (not shown). As best seen in FIGURES 1 and 3, lower housing 44 may also be provided with a pair of mounting flanges 49, disposed below and in vertical alignment with flange 46, and having holes 51 extending therethrough.

Although the slack adjuster assembly shown in the drawings is an automatic adjuster, it will be understood that the invention is not limited to an automatic adjuster and may be employed with a manual slack adjuster.

As best seen in FIGURE 3, housing 42 presents an internal general cylindrical chamber 50 which is in communication with a generally cylindrical chamber 52 presented by adjacent housing 44. Disposed within chamber 52 is a pawl mechanism of the type disclosed and described in my co-pending application, Serial No. 730,353, filed April 23, 1958. Inasmuch as the details of the pawl mechanism do not form a part of this invention, they are merely shown in diagrammatic form and, as seen in FIGURE 3, include a pawl carrying piston 54 which is moved to the right by compression spring 56 interposed between wall 47 of housing 44 and abutment 59 of the piston and which is moved to the left by pressure fluid received from a power cylinder (not shown) and which enters the chamber 52 through the inlet, indicated generally at 58.

Carried by the piston 54 and movable transversely thereof is a plunger 60 actuated by a spring 62 interposed between spring seat 61 of the piston and abutment 63 integral with the plunger and engageable with peripheral ratchet teeth 64 of a generally cylindrical ratchet member or sleeve 66 disposed for rotation within chamber 50 of housing 42.

As best seen in FIGURE 1, there is disposed within chamber 50 of housing 42 a pair of axially aligned left hand and right hand screws 68 and 70, respectively, which present oppositely threaded inner end portions 72 and 74, respectively, spaced from each other and which are threadably received within opposite ends of ratchet member 66.

The outer end of left hand screw 68 may be rigidly or non-rotatably secured to housing 42 in any desired manner as by a press fit within an aperture 76 presented by an end wall 78 of the housing; whereas right hand screw 70 is not rigidly secured to either the housing or the ratchet member and is therefore rotatable relative to the ratchet member and movable lineally relative to housing 42.

As best seen in FIGURES 1 and 2, slack adjuster 40 includes a brake lever mounting portion or supporting structure 80 which is preferably formed integrally so as to extend horizontally outward from the right hand end of slack adjuster housing 42.

As best seen in FIGURE 4, structure 80 includes a pair of spaced parallel horizontal arms 82 offset outwardly from, but preferably formed integrally with the sides or side walls 84 of housing 42. Each arm 82 com-

prises an outboard vertical wall 86 and a horizontal wall 88 formed integrally with and extending inboardly from the lower end of vertical wall 86. The inboard extremities of the horizontal walls 88 of the respective arms are spaced from each other to define an opening 90 therebetween, the purpose of which is explained hereinafter. The vertical walls 86 of the respective arms 82 are interconnected by an integrally formed generally horizontally extending upper wall or roof 92. As best seen in FIGURE 4, roof 92 comprises horizontal sections 94, which are preferably formed integrally with and which extend inboardly from the upper ends of the vertical walls 86 of the respective arms, and a central part-cylindrical section which merges at its ends with the inboard extremities of horizontal sections 94. The center section 96 is preferably a continuation of upper wall 98 of housing 42 so that sections 96 and 98 present an uninterrupted inwardly facing concave generally cylindrical surface 100.

At their outer extremities, vertical walls 86 of the respective arms 82 may be interconnected by a nut and bolt assembly 102 which has a dual function, namely: to add rigidity to the structure, and to serve as a stop or limit means for restricting the movement, in an outward direction, of traveling screw 70.

At its outboard end, traveling screw 70 presents an integrally formed head 104 having an aperture 106 extending horizontally therethrough.

The right hand or dead brake lever 20 may be either a double lever having spaced parallel elements 20a and 20b, as seen in FIGURE 4, or it may be a single lever provided at its upper end with a clevis (not shown). In either case, lever 20 may be pivotally connected to the head of traveling screw 70 by means of the preferably headless pivot or fulcrum pin 38.

In order to support brake lever 20 from the slack adjuster, there may be provided a pair of fulcrum elements 110 within which are journaled the opposite ends of pin 38 and which are supported by the lower horizontal walls 88 of the respective arms 82 for lineal movement thereon. These fulcrum elements may take the form of rollers as shown in FIGURES 1-4, adapted for rolling engagement with the walls 88, or they may be in the form of blocks 110a, as seen in FIGURE 5, adapted for sliding engagement with the horizontal walls 88 of arms 82. As best seen in FIGURE 4, horizontal upper section 94, vertical wall 86, and lower wall 88 of each arm 82 present inwardly facing surfaces 112, 114, and 116, respectively which define a generally U-shaped inwardly facing opening 118 within which is snugly received the related fulcrum element 110. The size of opening 118 is sufficient to permit the free sliding or rolling movement of the fulcrum element 110 or 110a upon the surface 116, but small enough to retain the fulcrum element within opening 118.

Thus, it will be understood that as slack in the linkage occurs as a result of normal wear of the parts, the automatic pawl mechanism will function to rotate ratchet member 66 in a counter-clockwise direction as seen in FIGURE 3, thereby causing traveling screw 70 to move in an outward direction or to the right as seen in FIGURES 1 and 2 and thereby carry related brake lever 20 closer to wheel 14 of the right hand wheel and axle assembly 12. The bolt of nut and bolt assembly 102 will serve to retain traveling screw 70 and brake lever 20 within the lever supporting structure 80 of the slack adjuster. The continuous cylindrical surface 100 of the slack adjuster housing and brake supporting structure will permit the ratchet member, which has a generally cylindrical outer periphery, to travel to the right as it is rotated by the pawl mechanism.

In order to adjust the position of the traveling screw relative to the ratchet member and also to the fixed screw, there may be provided a manual re-set nut 120 which is integral with ratchet member 66. The re-set nut may be provided at its outer periphery with spaced radial lugs 122, to permit the adjustment of the re-set nut by

hand, without the necessity of using a wrench or other tool. As best seen in FIGURE 4, opening 90 between horizontal walls 88 of arms 82 permits access to the re-set nut from underneath the structure 80.

In order to assemble the device after fixed screw 68 has been rigidly secured to housing 42, the ratchet member is inserted from the right hand end of the housing 42 and manually threaded onto the inner threaded end of fixed screw 68. To permit the free rotation of ratchet member 66, there may be provided a pawl release lever 124, as best seen in FIGURE 3, which is connected to the lower end of pawl plunger 60 by means of a pin 127 extending through an elongated slot 129 of lever 124 intermediate its ends and which is pivotally connected at one end by pin 126 to lugs 128 extending from the underside of housing 44. Thus, by depressing lever 124, pawl spring 62 is compressed as plunger 60 is moved downward to permit the free rotation of ratchet member 66. Once ratchet member 66 has been threaded onto fixed screw element 68, traveling screw 70 may be positioned at the opposite end of the ratchet member 66 outside of support structure 80, and then fulcrum pin 38 is inserted through head 104 of the screw and also through brake lever 20 and fulcrum elements 110. The traveling screw, lever, and fulcrum elements are then inserted into the brake support structure 80 from the right hand side as seen in FIGURE 1 and moved back until the inner threaded end 74 of screw 70 is in chamber 50 of housing 42 far enough so that ratchet member 66 may be rotated in the opposite or clockwise direction to bring its right hand end into engagement with the inner end of traveling screw 70. The re-set nut may then be adjusted and the nut and bolt assembly 102 applied to interconnect the arms 82 of brake support 80.

I claim:

1. In a brake arrangement for a vehicle having a frame and a supporting wheel and axle assembly presenting a rotatable friction surface, the combination of: friction shoe means disposed for frictional engagement with said surface; a generally vertically disposed brake lever pivotally connected to said friction shoe means; power means operatively connected to the brake lever for actuation thereof; and an automatic slack adjuster mounted on the frame, said slack adjuster presenting an opening for receiving said brake lever, said opening being elongated in the direction of slack adjustment, said slack adjuster presenting adjacent to and extending along the length of said opening substantially parallel upwardly and downwardly facing surfaces; and a fulcrum element pivotally connected to said brake lever and supported by and between said surfaces for lineal movement parallelly thereof and along the length of said opening, said element being the sole support of said lever for resisting the brake torque of the lever about said rotatable surface.

2. In an automatic slack adjuster assembly for varying the location of the fulcrum point of a depending brake lever in a brake arrangement for a railway truck comprising a brake shoe abuttable with a rotatable friction surface and a power cylinder operatively connected thereto, said shoe having a direct pivotal connection to said lever, the combination of: a frame structure; a traveling rotatable element having a bore therethrough, said bore having right and left hand internal threads at its opposite ends, respectively; a horizontal traveling screw, said rotatable element being oppositely threaded onto said screws and being rotatable relative thereto, said traveling screw being adapted to be pivotally connected to said lever; means to rotate the rotatable element and thereby change the location of said pivotal connection; and a fulcrum element adapted to be pivotally connected to said lever and supported by and between horizontal elements of said structure for lineal movement thereon parallelly thereof, said fulcrum element being the sole support of said lever for resisting the brake torque acting thereon about said rotatable surface.

3. In a automatic slack adjuster assembly for varying the location of the fulcrum point of a depending brake lever which is operatively connected between brake actuating means and friction means, the combination of: a frame structure; a pair of horizontal screws, one of said screws being non-rotatably secured to said structure, the other of said screws being movable relative to said structure and being adapted to be pivotally connected to the brake lever; a traveling ratchet member threadably interconnecting oppositely threaded end portions of the screws, whereby upon rotation of said member, said member moves axially of said secured screw, and said movable screw moves axially of said member; pawl means operable to rotate the ratchet member responsive to movement of the brake actuating means; said structure presenting roller means adapted to be pivoted to said brake lever and supported by said structure for rolling engagement therewith and lineal movement thereon.

4. In a brake arrangement for a vehicle having a frame and a pair of supporting wheel and axle assemblies presenting rotatable friction surfaces, the combination of: friction shoes disposed for engagement with said surfaces; generally vertically disposed brake levers directly pivotally connected to said friction shoes; power means pivotally connected to one of the brake levers for actuation thereof; and an automatic slack adjuster mounted on the frame and pivotally connected to the other of the brake levers, said slack adjuster including horizontal parallel spaced arms defining an opening therebetween for receiving said other brake lever; said opening being elongated in the direction of slack adjustment, a pair of fulcrum elements pivotally connected to said other brake lever and supported by and between the arms for lineal movement longitudinally thereof and in the direction of the length of the arms, said arms forming the sole bearing for said other lever to resist the brake torque of said other lever about the respective friction surface; and a rod pivotally interconnecting said levers.

5. A slack adjuster comprising a substantially cylindrical housing, said housing having horizontal spaced arms at one end thereof and defining therebetween an elongated opening extending longitudinally of said housing; a horizontal screw member substantially centrally disposed within said housing and fixed relative thereto at the other end thereof; a rotatable member having an outer periphery slidable within said housing and having an internally threaded longitudinal bore substantially centrally thereof; another horizontal screw member; said rotatable member being oppositely threaded at opposite ends thereof onto said screw members, and being rotatable in said housing; pivot elements, said elements and said other screw member having a mutual pivotal connection, said connection also being capable of incorporating connection with a brake lever extending into said housing through said opening, said elements being guided within said housing by and between said arms and adjacent said opening, and being actuated therein by the compound movement of the other screw member relative to said fixed screw upon rotation of said rotatable member relative to said screw member.

6. A slack adjuster according to claim 5, wherein said rotatable member has integral therewith at the end thereof adjacent said one end of the housing, means accessible for manual rotation thereof from externally of said housing.

7. In a railway brake slack adjuster, the combination of: a horizontally elongated housing having a top wall, spaced side walls, and spaced bottom walls connected to respective side walls; an adjusting member having a head slidably seated against the top wall; spaced lever elements at opposite sides of the head, said elements being spaced from the top wall and extending downwardly between the bottom walls for connection to associated brake means which exert upward and downward thrust

on said elements in response to braking torque; thrust members seated on respective bottom walls and supported solely thereby; pivot means interconnecting the elements with the head and with the thrust members; and horizontal adjusting means connected between said adjusting member and housing for moving the head and the elements and the thrust members along the length of the housing and thus in a path substantially normal to the pivot axis of said pivot means and for thereby adjusting position of said elements.

8. In a slack adjuster arrangement for adjusting slack of a brake arrangement including power cylinder means, a brake lever and friction means for a railway car truck, said adjuster comprising: a frame comprising a horizontal housing having elongated spaced arms forming thereby a pair of tracks; a pair of aligned horizontal screws, one of said screws being rigidly fixed to the frame and within said housing, the other of said screws being movable within the housing and between the tracks; a traveling ratchet member oppositely threaded onto the adjacent ends of said screws, said member being rotatable on said screws and movable within said housing axially of said screws; a pawl mechanism in said frame and operable to actuate said ratchet member upon movement of said power cylinder means; and pivot support members, said support members being guided by said tracks and pivotally connected to the opposite end of said traveling screw, said support member being adapted for supporting a brake lever.

9. In a railway brake slack adjuster, the combination of: a housing comprising a cylindrical portion and another portion having a top wall which is an extension of said cylindrical portion, said other portion having spaced side walls and spaced substantially horizontal bottom walls connected to respective side walls; a member in said housing and having a head with a surface complementary to and engaged with said top wall; spaced lever elements at opposite sides of said head; rollers seated on said bottom walls, respectively; pivot means connecting the head, the elements, and the rollers, said elements extending downwardly between said bottom walls for connection to associated brake means which develop upward and downward thrusts on said elements in response to braking torque on said brake means; and power means for effecting motion of said member longitudinally of and within said housing.

10. In a railway brake slack adjuster; the combination of a housing comprising a cylindrical portion and another portion having a top wall which is an extension of said cylindrical portion, said other portion having spaced side walls, and spaced substantially horizontal bottom walls, a screw having a head with a surface complementary to and engaged with said top wall, another screw fixed to said housing in axial alignment with the first mentioned screw, a ratchet rotatably mounted in said cylindrical portion in threaded engagement with said screws, spaced lever elements at opposite sides of said head, rollers seated in said bottom walls, respectively, pivot means connecting the head, the elements, and the rollers, said elements extending downwardly between said bottom walls for connection to associated brake means which develop upward and downward thrusts on said elements in response to braking torque on said brake means, and power means for actuating the ratchet.

11. In a railway brake slack adjuster; the combination of a housing comprising a cylindrical portion and another portion having a parti-cylindrical top wall which is an extension of a segment of said cylindrical portion, said other portion having spaced side walls, substantially horizontal sections joining respective side walls to said top wall, and spaced substantially horizontal bottom walls connected to respective side walls, a screw having a head with a parti-cylindrical surface complementary to and engaged with said top wall, another screw fixed

to said housing in axial alignment with the first mentioned screw, a ratchet rotatably mounted in said cylindrical portion in threaded engagement with said screws, spaced lever elements at opposite sides of said head, rollers seated on said bottom walls, respectively, beneath said sections, respectively, pivot means connecting the head, the elements, and the rollers, said elements extending downwardly between said bottom walls for connection to associated brake means which develop upward and downward thrusts on said elements in response to braking torque on said brake means, and power means for actuating the ratchet.

12. In a railway brake slack adjuster; the combination of a housing comprising a cylindrical portion and another portion having a parti-cylindrical top wall which is an extension of a segment of said cylindrical portion, said other portion having spaced side walls, substantially horizontal sections joining respective side walls to said top wall, and spaced substantially horizontal bottom walls connected to respective side walls, a screw having a head with a parti-cylindrical surface complementary to and engaged with said top wall, another screw fixed to said housing in axial alignment with the first mentioned screw, a ratchet rotatably mounted in said cylindrical portion in right-hand and left-hand threaded engagement with respective screws, spaced lever elements at opposite sides of said head, rollers seated on said bottom walls, respectively, beneath said sections, respectively, pivot means connecting the head, the elements, and the rollers, said elements extending downwardly between said bottom walls for connection to associated brake means which develop upward and downward thrusts on said elements in response to braking torque on said brake means, and power means for actuating the ratchet.

13. In a railway brake slack adjuster; the combination 35

5 of a housing comprising a cylindrical portion and another portion having a parti-cylindrical top wall which is an extension of a segment of said cylindrical portion, said other portion having spaced side walls, substantially horizontal sections joining respective side walls to said top wall, and spaced substantially horizontal bottom walls connected to respective side walls, a screw having a head with a parti-cylindrical surface complementary to and engaged with said top wall, another screw fixed to said 10 housing in axial alignment with the first mentioned screw, a ratchet rotatably mounted in said cylindrical portion in right-hand and left-hand threaded engagement with respective screws, spaced lever elements at opposite sides of said head, rollers seated on said bottom walls, respectively, beneath said sections, respectively, pivot means 15 connecting the head, the elements, and the rollers, said elements extending downwardly between said bottom walls for connection to associated brake means which develop upward and downward thrusts on said elements in response to braking torque on said brake means, power 20 means for actuating the ratchet, and manually operated means connected to the ratchet and accessible from between said bottom walls.
